UNITED STATES PATENT OFFICE.

GEORGE W. STAHL, OF CHICAGO, ILLINOIS.

PAINT-PACKAGE AND METHOD OF MAKING IT.

1,398,403.

Specification of Letters Patent. Patented Nov. 29, 1921.

Application filed November 3, 1920. Serial No. 421,481.

To all whom it may concern:

Be it known that I, GEORGE W. STAHL, a citizen of the United States, residing at Chicago, in the county of Cook and State of Illinois, have invented certain new and useful Improvements in Paint-Packages and Methods of Making Them, of which the following is a specification.

The invention relates to improvements in paint packages, and the general object of the invention is to provide an improved paint package comprising a hermetically sealed receptacle for containing ceramic paint.

Another object is to provide an improved paint package constructed of inexpensive material, and which is produced and assembled by an improved method, thereby effecting a large saving in the cost of manufacture.

The value and nature of ceramic paint require that it be marketed in sealed packages. It is a trade custom to use for that purpose a small package comprising a palette or base of vitreous material carrying a quantity of the paint spread upon a portion of its surface, and covered by a domed sheet of celluloid to protect the paint from moisture, dust and evaporation. To secure the cover to the base and provide for sealing the package it has been the common practice to employ a sheet metal tray as a receptacle for the base, and provided with a marginal rim which is clamped over the edges of the cover. Another type involves the use of a centrally apertured sheet metal plate arranged to overlie the cover and clamp it to the base by turning lugs formed on the edges of the plate under the base. It has been found also that in that type of package wherein the vitreous base is exposed the liability of breakage is great, and the protection of a backing, usually of tin, is desirable.

The consumer usually cuts away the celluloid cover to expose the paint for use. The packages being used but once, and of proportionately high cost in relation to the small amount of paint contained, the cost of their manufacture is an important consideration in the marketing of the paint. Sheet metal for the purpose is expensive and the operations required to shape the metal parts and seal them after packing, add materially to the cost.

A particular object of my invention is to provide a construction permitting the use

of much cheaper materials than heretofore used, and thus save a substantial portion of the cost of the package.

A further object is to provide a novel method of hermetically sealing such packages after being filled which further materially reduces the cost of their manufacture.

These objects are attained by eliminating the sheet metal and using cardboard or the like for the backing, and accomplishing thereby the added advantage of a superior protection against chipping or breaking the base.

By my method of assembling and sealing the parts, I avoid the shaping and crimping operations upon the edges of the cover and back, and seal the flat edges by applying a suitable impervious compound.

Other objects and advantages will be apparent as the description proceeds.

In the accompanying drawings, Figure 1 is a plan view of my improved package, with the sealing compound removed from a portion of one side. Fig. 2 is a transverse sectional view taken through the center of the package. Figs. 3 to 6 are reduced sectional views of the several parts representing the successive operations according to my improved method in the manufacturing assembly of the parts of the package.

In the embodiment illustrated, the invention comprises a palette or base 1 of glass or other vitreous material. A quantity of paint 2 is deposited upon the central portion of the base. A covering 3 preferably of transparent celluloid rests on the upper surface of the base and is shaped in general conformity to the dimensions of the base with its edges extending a substantial distance beyond the edges of the base. Centrally of the covering an upstanding convex portion 4 is formed over the deposit of paint and is of sufficient height to remain out of contact with the paint. An annular channel 5 is formed in the flange of the covering around the base of the convex portion to assure complete contact between the covering about the convex portion and the base, and to prevent buckling of the flat portion of the covering. Located beneath the base is a back member 6 also conforming with the general dimensions of the base and having its edges extending over the edges of the base and coincident with the outer edges of the cover. The back is cut from card-

board or other sheet material of a fibrous nature, and preferably is treated by a water-proofing process. At suitable points about the periphery of the package, the covering 5 and the back member are secured together outside of the edges of the base. Such points are preferably the central portion of opposite sides of the package in its usual rectangular shape. The fastening means may 10 be any suitable type of clamp or staple. In the embodiment illustrated, I have used common paper binding staples 7 driven through the edges of the covering and back and clenched. Fastening the edges by this means 15 draws them together outside of the base and holds the parts firmly in position. To seal the package substantially air-tight and to prevent moisture and dust from reaching the paint, I apply a layer of sealing wax 8 20 or other suitable impervious material about the edges of the package thus securing the covering and back in hermetically sealed relation. In applying the sealing compound, the stapled edges of the package preferably 25 are dipped in fluid wax. When the latter is partially solidified the edges may be subjected to pressure in a suitable mold or press to bring the edges of the cover and back into continuous contact and uniformly shape the 30 coating of sealing compound thereon. To obtain access to the paint for use, the celluloid covering may be cut about the edges of the base plate and removed. If desired, one edge may be left uncut to be used as a hinge 35 for turning back the covering.

It will be apparent that in my construction I have provided an exceedingly simple package which requires a small amount of labor and slight skill to assemble. The materials are inexpensive and make possible a 40 substantial reduction in the cost of manufacture as compared with the common types of package. By my simple method of stapling the overlapping edges of the cover 45 and the back, and of sealing them, I avoid the necessity for any die work in crimping or forming the engaging edges of those parts. The back of cardboard or similar fibrous material gives added protection to 50 the usual glass base in the package and prevents breakage in the handling of it as merchandise.

I claim as my invention:

1. A paint package comprising a base 55 adapted to receive a deposit of paint, a celluloid or like cover having a raised center portion and a flat rim overlying the face of said base, said rim extending a substantial distance beyond the edges of said base, a 60 back member of fibrous material underlying said base and having its edges coextensive with the edges of said cover, a plurality of

fasteners each securing together the edges of said cover and base along one side of the package, and a continuous rim of an impervious sealing compound or wax embracing 65 the said edges of the cover and base.

2. A paint package comprising a base, a celluloid or like cover having a raised center portion and a flat rim overlying said base, 70 said rim extending beyond the edges of said base for a substantial margin, a back member underlying said base and having flat edges coextensive with the edges of said cover, and a plurality of staples clamped 75 through the marginal edges of said cover and back to bind them together.

3. A paint package comprising a base, a celluloid or like cover having a raised center portion and a flat rim overlying said base, said rim extending beyond the edges of said base for a substantial margin, a back member of fibrous material underlying 80 said base and having flat edges co-extensive with the edges of said cover, the marginal edges of said cover and back being embraced by a continuous rim of wax applied thereto 85 to provide a sealed joint.

4. The method of assembling a paint package having a vitreous base, a celluloid or like cover, and a fibrous back, said cover and back being of greater dimensions than 90 said base, which comprises placing said cover and back upon the upper and lower surfaces respectively of said base with their overlapping edges coincident, fastening said edges together at a plurality of points without the periphery of said base, applying an impervious sealing compound in fluid condition continuously about the joined edges 100 of said cover and back so that the compound will externally embrace said edges, and pressing said edges into continuous contact about said base.

5. The method of assembling a paint 105 package having a vitreous base, a celluloid or like cover, and a fibrous back, said cover and back having flat rims of greater dimensions than said base, which comprises placing said cover and back upon the upper and lower surfaces respectively of said base and with their rims uniformly overextending said base, driving staples through the adjoining rims of said cover and back at spaced intervals, about said base, clenching the staples to hold said rims in contact, dipping said rims in fluid sealing compound, and applying pressure to said rims when said compound is partially solidified to seal them in continuous and uniform contact. 110 120

In testimony whereof, I have hereunto set my hand.

GEORGE W. STAHL.
